(57) **CLAIM**

The ornamental design for a multifunctional cup, as shown and described.

DESCRIPTION

FIG. 1 is a front, right and top perspective view of a multifunctional cup, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, right and top perspective view of the multifunctional cup of FIG. 1 in a usable state; and, FIG. 10 is an enlarged view of detail 10 in FIG. 1.

The broken lines shown in the drawings are included for the purpose of illustrating portions of the multifunctional cup that form no part of the claimed design.

1 Claim, 10 Drawing Sheets
